UNITED STATES PATENT OFFICE.

LANSING ONDERDONK, OF BOSTON, MASSACHUSETTS, ASSIGNOR TO THE UNION SPECIAL SEWING MACHINE COMPANY, OF CHICAGO, ILLINOIS.

CHAIN-STITCH SEWING-MACHINE.

SPECIFICATION forming part of Letters Patent No. 668,539, dated February 19, 1901.

Application filed November 9, 1897. Renewed August 1, 1900. Serial No. 25,589. (No model.)

To all whom it may concern:

Be it known that I, LANSING ONDERDONK, a citizen of the United States, residing at Boston, in the county of Suffolk, State of Massachusetts, have invented certain new and useful Improvements in Sewing-Machines, of which the following is a description, reference being had to the accompanying drawings and to the letters of reference marked *c* thereon.

My invention relates to an improvement in sewing-machines, and especially to the class of chain-stitch sewing-machines in which an under-thread-carrying looper co-operates with a thread-carrying needle to form stitches.

The object of the invention is to provide an arrangement of mechanism whereby the looper may, if desired, have only the forward and backward movements instead of the usual four motions, and whereby all danger of skipping stitches is avoided by the use of a "spreader" which seizes or moves against the looper-thread as the needle is about to come down and the looper about moving back and holds said thread at such an angle that the needle must pass down into its bight.

The invention consists in the matters hereinafter described, and referred to in the appended claims.

30 The invention is illustrated in the accompanying drawings, in which—

Figure 1 is a side elevation of so much of a sewing-machine as is necessary for a complete understanding of my invention. Fig. 2 is a cross-section on line 2 2 of Fig. 1; Fig. 3, a top view showing the relation of looper and spreader.

In the drawings, A represents the bed-plate of a sewing-machine of the chain-stitch type, and B the driving-shaft. The driving-shaft B is journaled at its forward end on the standard *a*, attached to the bed-plate of the machine, and forward of its front or outer bearing has attached to it a pin or rod C, the outer 40 end of which is provided with an eccentric *b*, while the portion adjacent the forward end of the shaft is bent, forming an inclined crank *c*, attached to the projecting arm *d* on the collar or head *e* on the forward end of the main 45 shaft.

Journalized to swing on its axis is a carrier

D, having wings *f*, which embrace the inclined crank *c*, upon which carrier is supported in any suitable way a looper or loopers *g*.

The loop-spreader *h*, as herein shown, is 55 supported on one of the arms of the rocking fork *k* in a socket *i* thereon, the fork at its lower end being sleeved on a stud *l*, secured in a lug *m* on the bed of the machine. This rocking yoke is oscillated by means of the eccentric *b* on the straight portion of the pin or rod *C*, and thus in the rotation of the driving-shaft B the looper-carrier is oscillated in the direction of the length of the looper and the spreader oscillated sidewise to catch the 60 looper-thread and deflect it, so that the needle *n* will go down into the bight of the looper-thread.

Instead of giving the spreader an oscillating movement it may be supported on a sliding bar which reciprocates back and forth in a right line.

Various minor modifications and changes in the construction of the parts of the device may be made without departing from the 75 spirit of my invention, the leading feature of which is the inclined crank arrangement or inclined crank and eccentric arrangement which operates both the looper and the loop-spreader.

Having thus described my invention, what I claim, and desire to secure by Letters Patent, is—

1. In a sewing-machine, a driving-shaft, a looper and a spreader, and means for positively operating the said looper and spreader, said means including an inclined crank having adjacent to one end an eccentric, said looper and spreader being engaged the one by the crank and the other by the eccentric, 85 and connections between the inclined crank and eccentric and the driving-shaft, substantially as described.

2. In a sewing-machine, a driving-shaft, an inclined crank and eccentric mounted on the 95 forward end thereof, a looper and a spreader, each operated by one of said elements whereby they have positive movements, the one in the direction of its length and the other laterally across the line traversed by the other; 100 substantially as described.

3. In a sewing-machine, a driving-shaft, an

inclined crank having on its outer end an eccentric, a loop-spreader, a pivoted spreader-support engaging said eccentric and a looper engaging the inclined crank; substantially as described.

4. In a sewing-machine, a driving-shaft, a looper, a loop-spreader, and means on the forward end of the driving-shaft for operating both the looper and spreader, said means in-

cluding an inclined crank operatively engaging one of said members; substantially as described.

In testimony whereof I affix my signature in presence of two witnesses.

LANSING ONDERDONK.
